(57) **CLAIM**

The ornamental design for a nail drill, as shown and described.

DESCRIPTION

FIG. 1 is a front, top perspective view of the nail drill showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures depict the portions of the article that form no parts of the claimed design.
